UNITED STATES PATENT OFFICE.

CHARLES D. DEWEY, OF FAIRFIELD, IOWA.

WASHING-MACHINE.

1,120,398.

Specification of Letters Patent. Patented Dec. 15, 1914.

Application filed October 24, 1912. Serial No. 727,544.

To all whom it may concern:

Be it known that I, CHARLES D. DEWEY, citizen of the United States of America, and resident of Fairfield, Jefferson county, 5 Iowa, have invented a new and useful Washing-Machine, of which the following is a specification.

One object of this invention is to provide an improved construction for washing machines.

A further object of this invention is to provide an improved means for carrying a dolly device on roller bearings.

A further object of this invention is to 15 provide improved means for driving the dolly mechanism of a washing machine from beneath a tub without any devices on or through the cover of the tub.

A further object of this invention is to 20 provide concentric stationary rubbing surfaces or wash-boards in a tub and an oscillating dolly device between said surfaces and adapted to move clothes relative to and rub them on both of said surfaces.

A further object of this invention is to 25 provide means for alternately pressing clothes downward and moving them in an arc in a tub.

My invention consists in the construction, 30 arrangement and combination of elements hereinafter set forth, pointed out in my claim and illustrated by the accompanying drawings, in which—

Figure 1 is a vertical section of a machine 35 embodying my invention. Fig. 2 is a plan, on an enlarged scale of parts of my improvement. Fig. 3 is a cross-section on an enlarged scale on the indicated line 3—3 of Fig. 1.

In the construction of the device as shown 40 the numeral 10 designates a tub preferably of cylindrical form, made of wooden staves and a plurality of legs suitably connected and bound together, and having an inclined bottom 11 directed toward a drainage faucet 12 in the wall. The tub also is provided with suitable handles such as 13 and a removable and replaceable cover 14, which cover may be made of sheet metal if desired. 45 A series of spaced rubber slats 15 are mounted vertically on and fixed to the inner surface of the wall of the tub 10 and form an outer rubbing surface or wash-board in said tub. A movable or false bottom 16 is mounted 50 loosely and preferably in level position within the tub 10 and is supported and

adapted to be lifted out manually by means of handles or lifting rods 17 arranged contiguous to the slats 15 and secured normally to hooks 18 in the wall of the tub. The 60 false bottom 16 preferably is provided with rubbing slats 19 on its upper surface. The false bottom 16 is formed with a central opening and a cylinder 20 extends through said opening and is fixed in water-tight 65 manner to the bottom 11 of the tub. A series of rubbing slats 21 are mounted vertically on and fixed to the outer surface of the cylinder 20 and form an inner rubbing surface or wash-board concentric with the 70 outer rubbing surface in the tub. A cap 22, of metal, is mounted on the upper end of the cylinder 20 and is secured rigidly thereto, and said cap is formed with a ball-race in its upper surface concentric with the 75 center of the cylinder and cap. A sleeve 23 is screwed through a hole in the center of the cap 22 and extends downward from said cap, centrally of the cylinder 20, through a central hole in the bottom 11 of 80 the tub, and is screwed, at its lower end, through the central portion of a bearing plate 24 fixed to the lower surface of said bottom. A shaft 25 is mounted loosely and centered in the sleeve 23 and is supported 85 by a ball bearing 25⁰ of conventional form on the upper end of said sleeve. A gear 26 is fixed to the lower end of the shaft 25 and is adapted to be driven by any suitable mechanism, not shown, beneath the tub. 90 An internal gear 27, formed with a ball race in its lower surface, is superposed on the cap 22 and is supported by balls 28 in the races of said gear and the sleeve 23. The internal gear 27 is formed with radial 95 and downwardly-curved arms 29, in this instance four in number, and said arms extend approximately to the center of the space between the concentric rubbing surfaces in the tub, and agitating paddles 30 100 are hinged on horizontal axes to the extremities of said arms and depend therefrom. It is the function of the paddles 30 to move clothes in an annular path between and agaiast the concentric rubbing surfaces 105 in the tub. The paddles also press the clothes toward the false bottom of the tub in reversing direction of travel as herein-after explained. A mutilated gear 31 is fixed to the upper end portion of the shaft 110 25 and is adapted to be driven continuously in one direction by said shaft. The muti-

lated gear meshes, during part of each revolution, with one of a pair of driving pinions 32, 33, which are in train with the internal gear 27 and are adapted to drive said internal gear somewhat less than one-half a revolution in the same direction as the mutilated gear is driven. The mutilated gear 31 is in mesh, during the major part of the remainder of each revolution, 10 with a reversing gear 34 opposite the pinion 32 and in train with the internal gear 27; and said reversing gear is adapted to drive said internal gear somewhat less than one-half a revolution in a direction opposite 15 to that in which the mutilated gear is driven. Thus is provision made for transforming rotary motion of the shaft 25 and

mutilated gear 31 into oscillatory motion of the gear ring and agitator.

I claim as my invention—

A washing machine, comprising a tub formed with an inclined bottom and having a faucet in its wall at the lower margin of said bottom, a perforated false bottom fitting loosely within said tub, supporting rods fixed to the false bottom, and supports on the wall of said tub for receiving said supporting rods.

Signed by me at Des Moines, Iowa, this twenty seventh day of September, 1912.

CHARLES D. DEWEY.
